[57] CLAIM

The ornamental design for a camera lens, as shown and described.

DESCRIPTION

FIG. 1 is a front and right side perspective view of a camera lens showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a front and right side perspective view of a camera lens shown with the broken lines removed for clarity of illustration.

FIG. 9 is a front elevational view of FIG. 8;

FIG. 10 is a rear elevational view of FIG. 8;

FIG. 11 is a top plan view of FIG. 8;

FIG. 12 is a bottom plan view of FIG. 8;

FIG. 13 is a left side elevational view of FIG. 8; and,

FIG. 14 is a right side elevational view of FIG. 8.

The broken lines shown in FIGS. 1-7 are to illustrate the environment only and form no part of the claimed design.
